Primary Examiner — Catherine S Posthauer*Assistant Examiner* — Lynette Marie Sample(74) Attorney, Agent, or Firm — Hawaii Patent Services;
 Nathaniel K. Fedde; Kenton N. Fedde(57) CLAIM

The ornamental design for a rice container, as shown and described.

DESCRIPTION

FIG. 1 is a perspective view of my new design, showing a rice container;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings illustrate portions of a rice container that form no part of the claimed design.

1 Claim, 8 Drawing Sheets(56)
